VALVED CLEANING NOZZLE WITH PLURAL MOUTHS FOR SUCTION CLEANERS

Louis E. Segesman, Canton, Ohio, assignor to The Hoover Company, North Canton, Ohio, a corporation of Ohio

Application March 5, 1949, Serial No. 79,767

5 Claims. (Cl. 15—416)

1

The present invention relates to suction cleaners and more particularly to a surface cleaning tool adapted to be attached to the end of a hose connected to a source of suction.

An object of the invention is to provide a surface cleaning tool having a pair of nozzles and valve means therefor so arranged in the tool body that dirt cannot interfere with the operation of the valve means. Another object is to provide a surface cleaning tool having two nozzles and valve means therefor, the valve means being assembled through the bottom of the tool body and sealed therein from dirt by a removable cover. A further object is to provide a surface cleaning tool having a removable nozzle lip to secure valve means in the tool body. Another object is to provide a novel and improved arrangement of valve means in a surface cleaning tool. Other objects and advantages of the invention will be apparent from the following description and drawings wherein:

Figure 1 is a front elevational view partly in section of my cleaning tool;

Figure 2 is a bottom plan view with parts broken away to more clearly disclose my construction;

Figure 3 is a section along line 3—3 of Figure 2 showing the valve in different operating positions;

Figure 4 is a section along the line 4—4 of Figure 2 showing the arrangement of the valve supporting shaft; and

Figure 5 is a section along the line 5—5 of Figure 2 with parts omitted showing the valve operating member in different positions.

The embodiment of the invention herein disclosed comprises a cleaning tool body 10 provided with a large rear nozzle 11 formed by two depending partitions 12 and 13 between which is arranged a portion of a removable cover member 15 having a top wall 16 which is secured to the body 10 by a pair of screws 17. The cover member 15 has side walls 18 and 19 contiguous with the partitions 12 and 13, and the wall 18 is provided with a portion defining the front nozzle lip 20 while the real wall 19 is provided with a surface engaging face 21 for the rear nozzle 11. A gasket 22 is arranged between the nozzle front lip 20 and the partition 12, and another gasket 23 is disposed between the partition 13 and a depending rear wall 24 of the body 10 to prevent entrance of dirt therebetween. An opening 25 is formed in the side and top walls 18 and 16 of the cover member 15 to connect the nozzle mouth 26 with an air passageway 27 centrally disposed in the body 10. A conduit 28 is rotatably connected to the body 10 by a swivel 29 and connects the air passageway 27 with an unshown source of suction, for example, a flexible hose attached to a suction cleaner.

Forwardly of the main nozzle 11 is a front nozzle 30 having its mouth 31 disposed centrally of the body 10 and of less extent in width than the main nozzle mouth 26. The nozzle 30 is formed by a front body wall 32 and a depending partition 33. The front nozzle 30 is connected to the air passageway 27 by a passageway 34 formed by interrupting the partition 33 at 35—35 and the partition 12 at 36—36, and the partitions 12 and 33 are joined by walls 37—37 to form an opening 38 which is controlled by a valve 39. A portion 15 of the cover member 15 covers the lower end of the partition 33 to form the front nozzle rear lip 40 and the gasket 22 prevents passage of air therebetween. A member 42 is attached by screws 43 to the body 10 and is provided with a notched edge 44 to form the front lip of the nozzle 30.

A partition 45 is disposed in the nozzle 30 and its lower edge 46 is spaced above the nozzle mouth 31. The partition 45 cooperates with the nozzle front wall 32 to provide a funnel 47 having a top inlet opening 48 and a lower outlet 49, the latter being above the nozzle lips 40 and 44 for passage of an air stream from above the nozzle mouth 31, as shown by arrows in Figure 3, to the air passageway 27 and thus to the source of suction.

Communication of either of the nozzle mouths 26 and 31 with the source of suction is controlled by the valve 39 provided with notched and smooth portions 70 and 71 respectively for selective engagement with the surface to be cleaned. The valve 39 is rigidly attached to a shaft 50 having its opposite ends arranged in spaced valve shaft housing 51—51 and the shaft is pivotally received in recesses 52 formed in the walls 37—37 and in spaced transverse partitions 53—53. The cover member 15 closes the housings 51—51 and engages the valve shaft 50 between the partitions 53—53 to hold the adjacent end of the shaft 50 assembled in the body 10. Arranged about the shaft 50 are gaskets 54 to prevent entrance of dirt into the valve shaft housings 51—51 so that the dirt cannot collect about the shaft 50 and interfere with its pivotal movements. Rigidly attached to one end of the shaft 50 is a member 55 having a recess 56 in which is disposed the bight portion 57 of a U-shaped spring 58 having angular ends 59—59 which are fitted in recesses 60—60 formed in the nozzle body 10. The member 55 has an arcuate surface 61 which rests 55 against the cover member 15 and the latter holds

the member 55 and thus the spring 58 and the adjacent end of the shaft 50 assembled in the body 10.

At the opposite end of the shaft 50 is an operating lever 65 which projects through an opening 66 in the body 10 and is provided at its upper end with a serrated surface 67 to receive the operator's foot for moving the valve 39 to its different positions. The opening 66 extends completely through the body 10 and its outlet 68 is between the nozzle mouths 26 and 31 and thus is subjected to the suction air stream passing through either of the nozzle mouths to the conduit 28 to prevent accumulation of dirt in the opening 66 which dirt would interfere with operation of the lever 65.

A brush 75 is disposed in a brush housing 76 and is attached to the body 10 by screws 77. Arranged about the body 10 is a furniture guard 78.

When the cleaning tool is in use the conduit 28 is connected to a source of suction, as for example, a suction cleaner. If it is desired to perform normal surface cleaning the large nozzle 11 is used, and its nozzle mouth 26 is connected to the source of suction by moving the lever 65 to the dotted line position shown in Figure 5, causing the valve 39 to be arranged in the dotted line position illustrated in Figure 3 to uncover the opening 25, and the valve is held in this position by the spring 58. In this position of the valve 39 the notched surface 70 forms part of the nozzle front lip and the small nozzle 39 is disconnected from the source of suction while the large nozzle mouth 26 is connected with the air passageway 27 and conduit 28 and thus the source of suction. The nozzle mouth 26 provides for passage of a relatively large volume and low velocity air stream to remove non-embedded dirt from the surface being cleaned.

If the dirt, threads, or other litter cannot be removed by the large nozzle mouth 26 then the smaller nozzle mouth 31 is employed. The small nozzle mouth 31 is connected to the source of suction by moving the lever 65 to the full line position in Figure 5 causing the valve 39 to be moved to its full line position illustrated in Figure 3, whereby the nozzle 39 is connected to the air passageway 27 and conduit 28. The funnel 47 is also connected with the atmosphere above the nozzle body by the inlet 48 and to the source of suction by its outlet 49. In this position of the valve 39 the smooth surface 71 on the valve contacts the surface being cleaned.

When the small nozzle mouth 31 engages the material being cleaned an air stream passes through the material and under the front lip 44 and the portions 71 and 40 of the rear lip. The air stream passing through the small nozzle mouth 31 is of greater velocity than that which flows through the larger nozzle mouth 26 and thus functions to remove litter clinging to the surface. An atmospheric air stream enters the funnel 47 through the inlet 48 above the surface being cleaned and passes through the outlet 49 into the air passageway 27 to the source of suction. This atmospheric air stream, as it passes beneath the lower end 46 of the partition 45, flows at a high velocity due to the constricted opening and enters the nap of the material exposed in the nozzle 31 to remove the clinging litter.

In order to assemble the valve 39 in the body 10 the opposite ends of the spring 58 are arranged in the recesses 60 and the valve shaft 50 is inserted in the recesses 52 while the recess 56 in the member 55 receives the spring 58 and the lever 65 is also inserted in the opening 66. There-

after, the cover member 15 is secured to the body 10 by the screws 17 and its inner surface contacts the arcuate face 61 of the member 55 and the shaft 50 between the partitions 53-53 to hold the valve shaft 50 in its recesses 52 to thereby assemble the parts in the body 10. The housing 51 in which the spring 58 is arranged is completely sealed and thus dirt cannot accumulate to interfere with operation of the spring 58 in holding the valve 39 in its adjusted position.

While I have shown and described but a single modification of my invention, it is to be understood that this modification is to be taken as illustrative only and not in a limiting sense. I do not wish to be limited to the particular structures shown and described, but to include all equivalent variations thereof except as limited by the scope of the claims.

I claim:

1. A cleaning tool comprising a body having two nozzles each provided with a surface engaging mouth arranged side by side in substantially the same plane, a conduit on said body for connecting said nozzle mouths to a source of suction, a valve in said body to control connection of either of said nozzle mouths to the source of suction, a shaft supporting said valve and rotatably mounted in said body and arranged adjacent the surface engaging mouths of said nozzles, an opening extending completely through said body and having its lower end substantially in said plane and exposed to the surface being cleaned, a valve operating member in said opening for operating said valve and having its lower end connected to said shaft and its upper end projecting beyond the top of said body for engagement by operator's foot, said opening having its lower end positioned intermediate said nozzle mouths to be subjected to the suction air stream passing through either of said nozzle mouths to thereby prevent accumulation of dirt in said opening.

2. A cleaning tool comprising a body having two nozzles, a conduit on said body for connecting said nozzles to a source of suction, a valve in said body operable independently of said conduit to control connection of either of said nozzles with the source of suction, a shaft supporting said valve and rotatably mounted in said body adjacent the surface engaging mouths of said nozzles, a housing in said body, resilient means in said housing connected to said shaft to maintain said valve in either of its adjusted positions, and a cover removably attached to the underside of said body and forming a lip for one of said nozzles, said cover when removed permitting arrangement of said valve, said shaft and resilient means in said body and upon attachment to said body said cover enclosing said valve supporting shaft and completing said housing to enclose said resilient means.

3. A cleaning tool comprising a body having two nozzles, valve means in said body movable to different positions to control connection of either of said nozzles to a source of suction, resilient means in said body to maintain said valve means in either of its positions, supporting means in said body to seat valve means and resilient means in said body, means defining an opening in said body for inserting said valve means and resilient means on said supporting means, and a cover for said opening removably attached to said body, said cover when removed exposing said opening for said insertion of said valve means and resilient means, and means on said cover for retaining said valve means and resilient means on

said supporting means upon attachment of said cover to said body.

4. A cleaning tool comprising a body having two nozzles, valve means in said body movable to different positions to control connection of either of said nozzles to a source of suction, over-center means connected to said valve means to maintain the latter in either of its positions and disposed in an open mouth recess in said body, and means forming a lip for one of said nozzles and engaging said over-center means to support the latter in said body and close said mouth of said recess.

5. A cleaning tool comprising a body having two nozzles, a conduit in said body for connecting said nozzles to a source of suction, valve means in said body movable to different positions to connect either of said nozzles with said conduit, manually operated means connected to said valve means independent of said conduit, means defining an opening in said body for inserting said valve means and operating means in said body, and a cover for said opening removably attached to said body, said cover when

removed exposing said opening for said insertion of said valve means and operating means, and means on said cover for retaining said valve means and operating means in said body upon attachment of said cover to said body.
